UNITED STATES PATENT OFFICE.

VIKTOR KAPLAN, OF BRUNN, CZECHOSLOVAKIA.

RUNNER WHEEL FOR TURBINES, ETC.

Application filed September 1, 1921. Serial No. 497,747.

To all whom it may concern:

Be it known that I, VIKTOR KAPLAN, a subject to the State of Czechoslovakia, residing at the Deutsche Technische Hochschule, 5 at Brunn, Czechoslovakia, have invented certain new and useful Improvements in Runner Wheels for Turbines, Etc. (for which I have made application for patent in Austria, on August 12th, 1919; Germany, 10 on December 30th, 1919; Czechoslovakia, on June 4th, 1920; Norway, on December 23rd, 1920; Sweden, on December 23rd, 1920; Great Britain, on January 10th, 1921; Italy, on January 14th, 1921; France, on January 15 19th, 1921; and Yugoslavia, on March 30th, 1921), of which the following is a specification.

My invention relates to water turbines, centrifugal pumps, etc., and has for its more 20 particular object improvements in the shape and relative position of the runner-blades, whereby an increase in the number of revolutions and in efficiency is obtained. To this end, the blades are made so that the mean 25 area of all the blades does not exceed one-third of the circular area determined by the diameter of the runner wheel. Moreover, the width of the blades measured in the direction of rotation decreases toward the 30 free ends of the blades.

In the accompanying drawing in which several runner-wheels, constructed according to the principle of my invention, are shown by way of example, Fig. 1 is the vertical 35 projection of a runner-wheel equipped with four blades of equal shape and size and adapted for a general axial water-flow. Fig. 2 is the horizontal projection of the wheel shown in Fig. 1. Fig. 3 shows a runner-wheel equipped with only two blades of equal shape and size, while Fig. 4 illustrates the horizontal projection of said runner-wheel.

In the modern construction of water turbines care must be taken to so regulate the 45 turbine that a definite permissible moment of the force is not continually exceeded. In the case where an electric generator is driven by a turbine, it is well-known, that the generator is only designed for a certain highest 50 speed, which must not be continually exceeded for the simple reason that the generator would be destroyed by the heat of the generator-windings. The usual regulating 55 devices cannot overcome this drawback but, on the contrary, increase it, because an in-

creasing moment of resistance on the part of the generator causes a reduction of its number of revolutions, which can only be compensated by a renewed increase of the 60 moment of the force. The said drawback can however be avoided, if the capacity of overloading of the generator is made to harmonize with that of the turbine. Figs. 1 and 2 show a runner-wheel of a water-turbine intended for high specific speeds. 65 The wheel, therefore, has only four, either fixed or adjustable, blades, whose entire blade surface (F) does not exceed a third of the circular area 70

$$\left(\frac{D^2x}{4}\right)$$

as determined by the diameter D of the runner wheel. In this case, the disturbance 75 of the normal flow through the runner-wheel is very slight, and a continual and considerable increase of the turning-moment causes a disturbance of the normal flow, producing a reduction of the moment of the force, not 80 an increase. By such an arrangement, the above mentioned danger of the generator being destroyed is effectually avoided. The said proportion of blade-surface and circular-area must of course not be considered 85 a fixed limit. On the contrary, there is a gradual variation, depending on the size of the runner-wheel, its roughness, and other conditions.

Figs. 3 and 4 show a runner-wheel adapted 90 for especially high specific speeds for low capacity in case of over-load. These requirements can only be met by a small number of blades, because otherwise the eddies caused by the blade-edges, an unfavorable 95 hydraulic radius, as well as practical manufacturing difficulties prevent the required objects from being attained. For these reasons, I provide such runner wheels with only two blades, which may be designed to be 100 adjusted so as to obtain a good efficiency in the case of variable admission.

The shape of the blades one must determine according to three dimensions, height, depth and width, taking into consideration 105 the water friction, if the theoretically calculated amount of water and number of revolutions are to be brought into agreement with the practical tests. For this reason, in the case of especially high specific speeds, 110 a reduction in the width of the runner-blades toward the suction-tube or toward

their free ends is necessary, in order to reduce the frictional resistance.

By the mean area F of the blades, the mean-value of the front and rear surface (5 f_1 and f_2 , Figs. 1 to 4) of the blades is meant. In the case of Figs. 1 and 2, therefore,

$$F = 4 \frac{f_1 + f_2}{2},$$

10

whereas in the case of Figs. 3 and 4

$$F = 2 \frac{f_1 + f_2}{2}.$$

15 Of course, the mean areas of the various runner-blades need not be alike, as long as the mean area of all the blades does not exceed one-third of the circular area referred to. This circular area determined by the 20 diameter D is fixed by the area of the circle which lies in a plane perpendicular to the turbine shaft, which circle is described by the blade-ends most distant from the runner shaft (Figs. 1 and 4). The manner and direction of the water-flow through the runner-wheel may be varied, as long as the runner-wheel is combined with devices as are absolutely necessary to obtain a well-controlled 25

flow without the least possible loss. If such a runner-wheel is to be mounted in a turbine, 30 a properly shaped guiding-device must be provided, to provide for a well-regulated water-supply. A suction-tube must also be provided for the discharge of the water, which must permit of a corresponding recovery of power through the suction-tube. 35

I claim as my invention:

1. Runner wheel for turbines and the like comprising blades the mean area of all of which is not greater than one-third of the 40 circular area determined by the diameter of the runner wheel.

2. A runner wheel for turbines and the like as set forth in claim 1 comprising only 45 two blades.

3. A runner wheel for turbines and the like as set forth in claim 1, in which the width of the blades measured in the direction of rotation decreases toward the free 50 end of the blades.

In testimony whereof I affix my signature in presence of two witnesses.

VIKTOR KAPLAN.
